Henry M. Smith INVENTOR
BY *Victor J. Evans* ATTORNEY

UNITED STATES PATENT OFFICE.

HENRY M. SMITH, OF OTTUMWA, IOWA.

GAGE AND LEVEL.

1,373,982.

Specification of Letters Patent.

Patented Apr. 5, 1921.

Application filed February 23, 1920. Serial No. 362,047.

To all whom it may concern:

Be it known that I, HENRY M. SMITH, a citizen of the United States, residing at Ottumwa, in the county of Wapello and 5 State of Iowa, have invented new and useful Improvements in Gages and Levels, of which the following is a specification.

This invention relates to a combined gage and level for railways and the principal objects of the invention is to provide 10 means for indicating the gage of the track and whether or not the track is level.

Another object of the invention is to provide 15 means whereby the device may be quickly and easily placed in position without requiring any manual adjustments of the parts.

This invention also consists in certain 20 other features of construction and in the combination and arrangement of the several parts, to be hereinafter fully described, illustrated in the accompanying drawings and specifically pointed out in the appended claims.

25 In describing my invention in detail, reference will be had to the accompanying drawings wherein like characters denote like or corresponding parts throughout the several views, and in which:—

30 Figure 1 is a view showing the device on the rails of a track.

Fig. 2 is an enlarged top view of the device with parts in section.

Fig. 3 is a detail view.

35 In these views 1 indicates a ring which is provided with a pair of sockets 2 which are arranged at diametrically opposite points thereon. Each of these sockets receives one end of a tube 3. The outer end of one tube 40 supports the forked member 4, the limbs of which are provided with downwardly extending projections 5. The outer end of the other tube is open and this tube slidably receives a bar 6 which has its outer end projecting from said tube and this end is recessed, as at 7 to fit against the rail and is also provided with a downwardly extending 45 projection 8 which is provided with an inclined part as shown. The bar 6 is forced

50 outwardly by means of the coil spring 9 located in the tube and pressing against the inner end of said bar. A slot 10 is formed adjacent the outer end of said tube through which an indicating mark 11 on said bar 55 may be seen. A gage plate 12 is secured to

the tube adjacent this slot with marks thereon coöperating with the mark on the bar.

In placing the device on the tracks the upper part of the ring 1 is seized by the hand and the device is lowered on the rails 60 with the forked member 4 engaging one rail and the end of the sliding bar engaging the other end. In lowering the device the inclined projection 8 will strike the head of the rail first and this will cause the bar to 65 slide inwardly against the pressure of the spring so as to permit the recess 7 to receive the rail. The projections 5 on the formed member will hold this end of the device in position on the other rail. By glancing 70 at the mark 11 appearing through the slot the gage may be determined from the gage on the plate. Thus it will be a simple matter to move the rail to secure the desired gage. 75

In order to use the device as a level for leveling the track I provide a spirit level 13 which is pivoted on an arm 14 within the ring so that it may rock in said ring. A lever 15 is connected to said level and this 80 lever extends along one side of the device and has its end pivoted to a bell crank lever 16 which is pivotally connected to the tube carrying the sliding bar. The upper part of this bell crank lever is provided with a 85 pointer 17 which is adapted to coöperate with suitable indicating marks on the segmental 18 which is carried by the tube.

When the device is placed on the rails the bubble in the spirit level will show whether 90 or not the track is level. If it is not level by moving the other end of the bell crank lever to cause the level to move into a horizontal position the degree of inclination may be determined from the pointer and 95 gage on the segmental plate.

It is thought from the foregoing description that the advantages and novel features of my invention will be readily apparent.

I desire it to be understood that I may 100 make changes in the construction and in the combination and arrangement of the several parts, provided that such changes fall within the scope of the appended claims.

What I claim is:—

1. A device of the class described comprising a ring, a pair of tubes having their inner ends connected with the ring at diametrically opposite points, a forked member at the outer end of one tube, prongs on 110

said forked member for engaging one rail of the track, a sliding bar carried by the other tube, a spring in said tube for forcing the bar outwardly and indicating means associated with the bar and tube for indicating the gage of the track.

2. A device of the class described comprising a member having one end formed to engage one rail of the track, a sliding bar carried by the other end of said member, a spring for forcing said bar outwardly, said bar having its outer end recessed to engage the rail, an inclined projection on said bar for engaging the rail to move the bar to cause its recess to engage the rail and gage means associated with said bar and member.

3. A device of the class described com-

prising a ring, a pair of tubes having their inner ends connected with the ring at diametrically opposite points, a rail engaging member at the outer end of one of said tubes, a bar slidably supported in the other tube and having a rail engaging part on its outer end, a support in the ring, a spirit level pivoted to said support, a bell crank pivoted to one of the tubes and having a hand engaging part, a lever connecting said bell crank with the level and a gage plate carried by the tube and coöperating with said handle part of the bell crank.

In testimony whereof I affix my signature.

HENRY M. SMITH.
